US00D349712S

United States Patent [19]

Janczak

[11] Patent Number: Des. 349,712

[45] Date of Patent: ** Aug. 16, 1994

[54] COMBUSTION ENGINE DRIVEN WOOD SPLITTING MACHINE

[75] Inventor: **Jerzy Janczak**, S:t Mickelsgatan, Sweden

[73] Assignee: **Jonsered Power Products AB**, Partille, Sweden

[**] Term: 14 Years

[21] Appl. No.: 7,675

[22] Filed: Apr. 30, 1993

[30] Foreign Application Priority Data

Nov. 4, 1992 [SE] Sweden 92-2317

[52] U.S. Cl. D15/127

[57] CLAIM

The ornamental design for a combustion engine driven wood splitting machine, as shown and described.

DESCRIPTION

FIG. 1 is a front, top and right side perspective view of a combustion engine driven wood splitting machine showing my new design; and, FIG. 2 is a rear, top and left side perspective view thereof.

The bottom is plain and unadorned.

FIG. 1

FIG. 2
